FLUID DELIVERY AND MONITORING APPARATUS

Stephens N. Sato, San Diego, Calif., assignor to Ivac
Corporation, San Diego, Calif., a corporation of
California

Filed June 2, 1969, Ser. No. 17,476

Term of patent 14 years

Int. Cl. D29—02

U.S. Cl. D83—1

Fig. 4

Fig. 5

FIG. 1 is a perspective view of a fluid delivery and monitoring apparatus embodying my new design;

FIG. 2 is a left side elevational view of the apparatus shown in FIG. 1;

FIG. 3 is a rear elevational view of the apparatus shown in FIG. 1;

FIG. 4 is a top plan view of the apparatus shown in FIG. 1; and

FIG. 5 is a bottom plan view of the apparatus shown in FIG. 1.

I claim:

The ornamental design for a fluid delivery and monitoring apparatus, as shown.
